Peter Lawson, Lowell, Massachusetts.

Letters Patent No 167, dated 22nd February 1848

The Schedule referred to in these Letters Patent and making part of the same.

To all to whom these presents shall come:

Be it known that I, Peter Lawson of Lowell, in the County of Middlesex and State of Massachusetts have invented or produced a new design or figure to be woven into carpets and other fabrics and that the following is a full, clear, and exact description of the principle or character which distinguishes it from all other things before known, reference being had to the accompanying drawing which forms a part of this description and numbered 660 --

This design consists of two large figures, the details of which are as follows, the largest of the two figures, A, is a die, surrounded by an irregular formed border, consisting of a light stripe a around the outside, within which there is a vine and leaves b, and again within this the inner edge of the border is terminated by a double intertwined cord or stripe C, which is indented, and has a curved portion at each end, the ground is striped with bands of different colours, as follows: a ruby stripe, a red shaded stripe, a green shaded stripe then a red, and then a blue, and at the centre a red stripe; in the centre there is an oblong die, d, pointed at each end and surrounded by a foliate ornament e, each of the stripes is covered with a fine tracery figure. Beyond the principal figure just described, there is a rose f, from which springs a foliate branch g, that runs diagonally across, over a ruby ground, and connects with an irregular eight pointed star h over which are small leaf sprigs, and a rose centre. It is obvious that the colours in this pattern can be varied without changing the figure.

Having thus fully described my design to be worn in to carpets, What I claim and desire to secure by Letters Patent, is the figures above described, and in combination therewith the combinations of colours as above set forth.
